UNITED STATES PATENT OFFICE.

WILLIAM M. LAYTON, OF MANSFIELD, OHIO.

TURNTABLE.

Application filed April 1, 1925. Serial No. 19,836.

This invention relates to a self-acting turn table and while capable of general use for turning vehicles such as automobiles or locomotives, the present invention is directed 5 particularly to an automatic turn table for use in connection with toy electric railway systems.

The primary object of the present invention is to provide an automatic turn table 10 which may be connected in the track system and which shall be capable of receiving and automatically stopping the electric locomotive or train, turning such locomotive or train through 180°, and then applying power 15 to the locomotive to cause the same to automatically leave the turn table and pass over the track system.

Another object is to provide a turn table 20 of the aforesaid character which shall be simple in construction, inexpensive to manufacture, and which shall be positive and reliable in action so that the train may operate continuously without the necessity of the operator handling the locomotive or any 25 part of the system.

With these and other objects in view, the invention consists in the various novel features of construction and arrangement or combination, all of which will be fully described hereinafter and pointed out in the 30 appended claims.

In the drawings accompanying and forming part of this application, Fig. 1 is a fragmentary side elevation of a railway system showing my turn table operatively connected thereto and showing an electric locomotive about to be received or about to leave the turn table; Fig. 2 is a similar view but showing the locomotive in position on the turn table and ready to be rotated to 180°; Fig. 3 is a top plan view of the turn table and a portion of the associated rail system; Fig. 4 is a transverse sectional view taken on the line 4—4 of Fig. 3; and Fig. 5 is a detail longitudinal sectional view through a portion of the turn table and post therefor.

Describing the various parts by reference characters, 1 denotes a base which is preferably formed from sheet metal and provided with an upwardly embossed portion 2 which is adapted to support the turn table and associated mechanism. Fastened adjacent one end of the base is a pair of spaced curved tracks 3 and 4 which have their upper edges arranged to define an inclined plane, and rising from the center point of such tracks

is a pivot post 4a. This post may be fastened to the base in any suitable manner as by riveting over the underside thereof as indicated at 5. The upper end of post 4a 60 is reduced in diameter, as indicated at 6 and the upper end thereof is sharpened as at 7. Pivots mounted on the sharpened end of post 4a is a turn table comprising a channeled-shaped sheet metal supporting member 9 which carries a center rail 10 and outside rails 11, 11, the latter being fastened by screws 12 to the flanges 13 of the supporting member 9 and insulated therefrom by suitable insulating material 14 interposed therebetween. It will be noted from Fig. 5 that I preferably form member 9 with an elongated longitudinally disposed aperture 14a and center rail 10 with an enlarged socket 14b so as to permit free tilting movement of 75 the turn table about post 4a as well as rotary movement thereabout as will be explained hereinafter. The center rail 10 is continuous from one end of the turn table to the other, while the outer rails 11 are divided 80 on each side of the support 9 into two sections as clearly shown in Figs. 1 and 2, these sections being insulated, one from the other by the aforementioned insulation 14 and also by an air gap 15 separating such sections. The inner abutting ends of these rail sections are provided with an arcuate depression 16 which are adapted to receive the wheels of the locomotive 17 as will be more 85 fully explained hereinafter. Fastened to a 90 pair of rail sections 11 along one side of the turn table adjacent each outer end thereof, is a metallic extension 19, and these extensions are adapted to contact with the outer rails 26 of the stationary track to limit the 95 rotary movement of the turn table. On the under side and adjacent each end of the turn table is fastened a pair of brackets 21, 21 which pivotally support an anti-friction roller 22. One of these rollers is adapted to 100 engage curved track 3 while the other of said rollers is adapted to engage curved track 4 and thereby facilitate the rotation of the turn table about its pivotal point.

Adjacent the lower end of the curved tracks 3 and 4 there is positioned a section of stationary track 20, a portion of which is preferably inclined at an angle slightly less than the normal angle of inclination of the turn table. This sectional track may be conveniently supported by a sheet metal member 24 which extends transversely be-

neath the rails of the track section and is provided with embossed portions 25 that are adapted to embrace the lower portion of the rails. In this connection it will be noted by referring to Fig. 3 that the two outer rails 26 of the track section 20 are insulated from the support 24 by suitable insulating material 27 interposed between the embossed portions 25 and the rails 26. The center rail 27^a is in electrical contact with the support 24 and also with the base 1. Each of the outer rail sections 26 has fastened thereto adjacent one end, a flexible contact strip 28 which is adapted to be engaged by the aforementioned projections 19 on the turn table and thereby permit a transfer of electrical energy from the rails 26 to the turn table rail sections 11 depending upon which projection 19 and contact 28 are engaged. These contact strips also serve to hold the turn table in alignment with the stationary track section after the locomotive has left the turn table.

In operation the stationary track section 20 is connected to the track system at any desired point. A locomotive 17 or other electrical vehicle proceeding over track section 20 will continue up the turn table as shown in Fig. 1 until the rear wheels of such vehicle are engaged in the upper arcuate depressions 16 of the rail sections 11, current being supplied to the turn table through the center rail 27^a of the track system, support 24, base 1, and pivot post 4^a to the center rail 10 of the turn table. Current then flows through the usual brushes 30 of the vehicle and through the electric motor to the wheels thereof. It will be obvious that so long as the wheels of the vehicle are in contact with the lower rail sections 11 of the turn table, current may flow as previously described, thence through the wheels of the vehicle, lower track sections 11 and through projection 19 and contact 28 to one of the rails 26. The momentum of the vehicle is sufficient to carry the same over the small air gap 15 between the rail sections 11, at which point the current will be broken and the locomotive will come to rest with the rear wheels thereof in the arcuate depressions 16 of the upper rail sections as shown in Fig. 2. The weight of the vehicle will cause the turn table to rock about its longitudinal axis, depressing the upper end thereof until roller 22 engages with curved track 4, whereupon the weight of the vehicle will cause the turn table to rotate by gravity down the incline plane of the curved track. The turn table with the vehicle thereon will thus turn through 180° or until the upper projection 19 engages the other rail 26 of track section 20. When the turn table has completed its rotary movement it will be noted that current is now free to flow from the center rail 27^a to the center rail 10 of

the turn table, as previously described and thence through the motor to the wheels of the vehicle and through the track section 11, projection 19 and contact 28 to the other rail 26. The vehicle motor is thus energized causing the vehicle to automatically leave the turn table and proceed over the track system in an opposite direction. When the locomotive again approaches the turn table the same operation will take place but in this instance the turn table will rotate in an opposite direction to cause the other projection 19 to swing about and engage the rail section 26.

From the foregoing description it will be apparent that the turn table is entirely automatic in operation, it being always in position to receive a vehicle and when such vehicle is positioned thereon, the current will be automatically broken whereupon the turn table will operate to reverse the position of the vehicle and current will be again automatically supplied to cause the vehicle to move thereoff of its own power.

If desired suitable side plates 30 as indicated by dot-and-dash lines, may be fastened along the sides of the turn table to insure the locomotive remaining on the rails of the turn table during the rotary movement thereof and particularly at the instant when the turn table is stopped by extension 19 engaging rail 26.

Having thus described my invention, what I claim is:

1. An automatic turntable comprising a plurality of independent inclined curved track sections, a pivot post, a turntable rotatively mounted on said pivot post, rollers disposed beneath said turntable and in alignment with said track sections, and means for permitting a tilting movement of said turntable about said pivot post to engage certain of said rollers with its respective track section and automatically start said turn table rotating.

2. An automatic turntable comprising a plurality of independent inclined curved track sections, a pivot post, a turntable rotatively mounted on said pivot post, rollers disposed beneath said turntable and in alignment with said track sections, means for permitting a tilting movement of said turntable about said pivot post to engage certain of said rollers with its respective track section, and means for limiting rotational movement of said turntable through 180°.

3. An automatic turntable comprising inclined curved track sections, a pivot post, a turntable rotatively mounted on said pivot post, rollers disposed beneath said turntable and in alignment with said track sections, means for permitting a tilting movement of said turntable about said pivot post to engage certain of said rollers with its respec-

5 tive track section, a stationary track disposed in operative relation with respect to said turntable, and means for stopping the rotational movement of said turntable in either direction in alignment with said stationary track.

4. An automatic turntable for electric railways comprising a base, a stationary track mounted on said base, a turntable arranged 10 on an incline and disposed in operative relation to said stationary track, means for rotatively supporting said turntable and permitting a tilting movement of said turntable about the longitudinal axis thereof, said 15 turntable having pairs of rail sections thereon insulated from each other, and means for automatically electrically connecting the lower rail sections with the stationary track, and disconnecting the upper rail sections 20 therefrom.

5. An automatic turntable for electric railways comprising a base, a stationary track mounted on said base, a turntable arranged 25 on an incline and disposed in operative relation to said stationary track, said turntable being rotatable about an axis to position either end thereof in alignment with said stationary track, said turntable having pairs of rail sections thereon electrically insulated 30 from each other, and means for automatically electrically connecting the lower rail sections with said stationary track and disconnecting the upper rail sections therefrom.

6. An automatic turntable for electric railways comprising a base, a stationary track mounted on said base, a turntable arranged 35 on an incline and disposed in operative relation to said stationary track, said turntable being rotatable by gravity about an axis to position either end thereof in alignment with said stationary track, said turntable having pairs of rail sections thereon electrically insulated from each other, means for automatically electrically connecting the lower 40 rail sections with said stationary track and disconnecting the upper rail sections therefrom, and additional means for stopping an electric vehicle on said upper rail sections.

7. An automatic turntable for electric railways comprising a base, a stationary inclined track mounted on said base, a pair of inclined curved tracks mounted on said base, a pivot post rising from said base, a turntable rotatively mounted on said post and disposed in operative relation to said stationary track, a roller disposed beneath each end portion of said turntable, said turntable being adapted to tilt on said post to engage either of said rollers with its respective curved track, said turntable having pairs of rail sections insulated from each other, and means for automatically electrically connecting the lower rail sections with said stationary track and disconnecting the upper rail sections therefrom.

8. An automatic turntable comprising a base, a stationary track mounted on said base, a turntable arranged on an incline and in operative relation to said track, means for automatically stopping an electric vehicle 70 adjacent the upper end of said turntable, means for rotating said turntable and vehicle through a predetermined angle, and means for automatically starting said vehicle from said turntable. 75

9. An automatic turntable comprising a base, a stationary track carried by said base, a pivot post, a turntable rotatively mounted on said pivot post and arranged on an incline, means for temporarily holding said turntable in operative relation to said stationary track, means for automatically stopping an electric vehicle adjacent the upper end of said turntable, means for automatically rotating said turntable and vehicle 80 through 180°, and means for automatically starting said vehicle when said turntable is in alignment with said stationary track.

10. An automatic turntable comprising a base, a stationary track carried by said base, a pivot post, a turntable rotatively mounted on said pivot post and arranged on an incline, means for automatically stopping a vehicle adjacent the upper end of said turntable, means for automatically rotating said turntable and vehicle through 180° means for stopping said turntable in alignment with said stationary track, side plates carried by said turntable for preventing the vehicle 90 from leaving the turntable due to the impact of stopping, and means for automatically starting said vehicle when said turn table is in alignment with said stationary track. 95

11. An automatic turntable comprising a base, a pivot post rising from said base, a turntable normally arranged on an incline and rotatively mounted on said pivot post, a stationary track disposed in operative relation to said turn table and arranged on an incline, and means for permitting a tilting movement of said turntable longitudinally about said pivot post as a fulcrum, thereby to change the angle of inclination of said turntable and automatically permit the same to rotate over a predetermined arc by 100 gravity. 105

12. An automatic turntable comprising a base, a pivot post rising from said base, an inclined curved track section mounted on said base, a turntable normally disposed on an incline and rotatively mounted on said pivot post, rollers disposed beneath said turntable in alignment with said track section, a stationary track disposed in operative relation to said turn table and arranged on an incline and means for permitting a tilting movement of said turntable longitudinally about said pivot post as a fulcrum to engage said rollers with said track section and thereby permit said turntable to automatically 110 120 125 130

rotate over a predetermined arc by gravity.

13. An automatic turntable for electric railways comprising a stationary track, a pivot post, a turntable disposed in operative relation to said stationary track, said turntable being rotatively mounted on said pivot post, means for supplying electrical energy to a vehicle from a section of said turntable, additional means for disconnecting said vehicle from the source of electrical energy, and means for permitting a limited tilting movement of said turntable longitudinally about said pivot post as a fulcrum, thereby to change the angle of inclination of said turntable and permit the same to rotate over a predetermined arc by gravity.

14. An automatic turntable for electric railways comprising a base, a stationary track mounted on said base, a pivot post rising from said base, two independent spaced inclined curved track sections mounted on said base, a turntable normally arranged on an incline and disposed in operative relation to said stationary track, said turntable being rotatively mounted on said pivot post, means carried by said turn table for supplying electrical energy to a vehicle thereon, additional means carried by said turn table for disconnecting said vehicle from the source of electrical energy, rollers disposed underneath said turntable and in alignment with said track sections, and means for permitting a tilting movement of said turntable longitudinally about said pivot post as a fulcrum to engage said rollers with their respective track sections.

15. An automatic turntable for electric railways comprising a base, a stationary track mounted on said base, a pivot post rising from said base, two independent spaced inclined curved track sections mounted on said base, a turntable normally arranged on an incline and disposed in operative relation to said stationary track, said turntable being rotatively mounted on said pivot post, rollers disposed underneath said turntable and in alignment with said track sections, means for permitting a tilting movement of said turntable longitudinally about said pivot post as a fulcrum to engage said rollers with their respective track sections, thereby to change the angle of inclination of said turntable and permit the same to automatically start to rotate over a predetermined arc by gravity, and means for stopping rotational movement of said turntable in either direction in alignment with said stationary track.

16. An automatic turntable for electric railways comprising a stationary track, a

turntable arranged on an incline and disposed in operative relation to said stationary track, means for rotatably supporting said turntable, means for permitting a tilting movement of said turntable about the longitudinal axis thereof, rails carried by said turntable for receiving an electric vehicle, means for disrupting the flow of electric energy to a vehicle on said turntable at a predetermined point thereon, and means for automatically rotating said turntable and vehicle through a predetermined angle.

17. An automatic turntable for electric railways comprising a stationary track, a turntable arranged on an incline and disposed in operative relation to said stationary track, means for rotatably supporting said turntable, means for permitting a tilting movement of said turntable about the longitudinal axis thereof, rails carried by said turntable for receiving an electric vehicle, means for disrupting the flow of electric energy to a vehicle on said turntable at a predetermined point thereon, means for automatically rotating said turntable and vehicle through a predetermined angle, and means for establishing the flow of electric energy to said vehicle to cause the same to leave the turntable.

18. An automatic turn table for electric railways comprising one or more stationary tracks, a turn table disposed in operative relation to said stationary tracks, means rotatably supporting said turn table, means for permitting a tilting movement of said turn table about the longitudinal axis thereof, rails carried by said turn table for receiving an electric vehicle, means for disrupting the flow of electric energy to a vehicle on said turntable, means for holding said vehicle stationary on said turn table, means for automatically rotating said turn table and vehicle through a predetermined angle, and means for establishing the flow of electric energy to said vehicle to cause the same to leave the turn table.

19. An automatic turn table comprising a base, a pivot post, a turn table rotatively mounted on said post, rails carried by said turntable for receiving an electric vehicle, means for automatically stopping an electric vehicle on said turn table, means for holding said vehicle stationary on said turn table, means for automatically rotating said turn table and vehicle through a predetermined angle, and means for automatically causing said vehicle to leave said turn table.

In testimony whereof, I hereunto affix my signature.

WILLIAM M. LAYTON.
